US0D1043106S

(12) United States Design Patent (10) Patent No.: US D1,043,106 S
(45) Date of Patent:  Sep. 24, 2024

(54) CARD HOLDER WALLET

(71) Applicant: Xianhai Zhang, Ganzhou (CN)

(72) Inventor: Xianhai Zhang, Ganzhou (CN)

() Term: 15 Years

(21) Appl. No.: 29/802,319

(22) Filed: Aug. 4, 2021

(30) Foreign Application Priority Data

Jun. 10, 2021 (CN) 202130360592.9

(51) LOC (14) Cl. 03-01

(52) U.S. Cl.

USPC D3/251; D3/247
